APPARATUS FOR CASTING HOLLOW ARTICLES

Matthew Wagner, Los Angeles, Calif.

Application September 29, 1933, Serial No. 691,536
Renewed April 24, 1935

8 Claims. (Cl. 22—153)

This invention relates to improvements in apparatus for and method of making hollow articles.

The general object of the invention is to provide an improved apparatus for moulding hollow articles.

Another object of the invention is to provide an improved mould for casting hollow articles such as bath tubs having a skirt along one side thereof.

10 A further object of my invention is to provide a novel method of making hollow articles.

Other objects and advantages of this invention will be apparent from the following description taken in connection with the accompanying drawings wherein:

Fig. 1 is a side elevation of my improved mould apparatus with portions thereof in section;

Fig. 2 is a section taken on line 2—2 of Fig. 1 on a reduced scale;

20 Fig. 3 is a section taken on line 3—3 of Fig. 1 on a reduced scale;

Fig. 4 is a section taken on line 4—4 of Fig. 1 on a reduced scale;

Fig. 5 is a perspective view of one of the sand core members;

Fig. 6 is an enlarged section taken on line 6—6 of Fig. 1;

Fig. 7 is a section taken on line 7—7 of Fig. 6, and

Fig. 8 is a section taken on line 8—8 of Fig. 6.

Referring to the drawings by reference characters I have indicated my improved apparatus generally at 10. As shown the mechanism 10 is adapted to manufacture bath tubs and includes a mould member which is indicated generally at 12. The mould member comprises a base section 13, a body portion 14, a top section 15, a core plunger 16 and a skirt plunger 17.

40 The mould 12 is adapted to form a bath tub from moulten material, such as metal. The bath tub 18 includes the usual hollow body 19 having a top flange 20 therearound and with a depending skirt 21 along one side and having a rib 22 adjacent each end. Each rib at one end joins the skirt 21 adjacent the lower end thereof and at the opposite end joins the flange 20 adjacent the center of the tub.

45 The mould 12 is adapted to form the bath tub inverted as is the customary practice. The base 13 includes a bottom portion 23 and an upwardly extending flange portion 24. In the bottom portion 23 of the base an aperture 25 is provided and the upper face 26 of the bottom portion is plane while the inner face 27 of the flange por-

tion is shaped to form a recessed panel in the tub skirt 21 as indicated at 28.

The body portion 14 of the mould is positioned on the base 13 and has an aperture 29 therein which conforms to the shape of the outside of the tub body. The upper face of the body portion 14 is flush with the upper surface of the base flange 24 and in the underface of the body portion 14 I provide a recessed portion 30 in which the flange portion 20 of the tub is formed. Furthermore, in 10 the underface of the member 15 I provide gas outlet grooves 30' which at one end communicate with the recess 30 and at their opposite ends open through the side faces of the body.

15 The top section 15 is positioned over the upper faces of the body section 14 and the flange portion 24 and includes a recess 31 in its underface which is shaped to form a portion of the outside of the tub body.

20 Adjacent the rear thereof the top section 15 includes an aperture 32 having positioned therein at each end a plug member 33 which forms a chamber 34. The plug members 33 are secured to the top section in any desired manner and extend to the center of the tub at each end thereof and 25 are shaped to conform to the outer face of the tub.

20 The plug members extend downward through apertures 35 in the body section 15 to the underface of the tub flange 20 and are recessed as at 36 30 to form the end sections of the skirt 21.

35 Each of the plug members 33 includes a triangular shaped recess 37 in which a sand core 38 is adapted to be positioned. The core 38 has a groove 39 therein in which the rib 22 of the tub 35 is formed. The skirt plunger 17 is positioned in the chamber 34 of the top section and like the plugs 33 extends downward through the aperture 35 in the body 14 to the under surface of the top flange 20. One face of the plunger 17 is 40 shaped as indicated at 40 to conform to the outer surface of the tub and the opposite face of the plunger is shaped as indicated at 41 to conform to the inner surface of the tub skirt 21.

45 In the underface of the top section 15 I provide a plurality of gas outlet grooves 42 which at one end communicate with the recess 31 and at the opposite ends open through the side walls of the section 15. Intermediate the length and width of the tub bottom in the top section 15 I 50 provide an aperture 43 and a communicating recess 44 in which a sand pouring plug 45 is positioned. The underface of the pouring plug 45 is shaped to conform to a portion of the under surface of the tub bottom. The pouring plug 45 55

further includes an open topped recess 46 and is provided with a plurality of apertures 47 which at one end communicate with the recess 46 and at the opposite end open through the under face 5 of the pouring plug.

5 The core plug 16 includes a lower portion 48 which is positioned in the aperture 25 of the base 13 and has a sliding fit therein. The core plug 16 further includes an upper portion 49 which 10 is positioned in the aperture 29 of the body section 14 and in the recess 31 of the top section 15. The upper portion 49 of the core plug is shaped to conform to the inner surface of the tub body.

The core plug 16 is supported adjacent each end 15 on a cam member 50 which engages wear plate 51 on the core plug. The cam members 50 are mounted on a shaft 52 which is journaled in bearings 53 and includes a crank portion 54 intermediate its length. Pivottally mounted on the crank 20 portion 54 of the shaft I provide a pitman 55 which is in turn pivotally secured as at 56 to a piston rod 57 and which is secured to a piston 58 positioned in a cylinder 59.

Fluid conduits as indicated at 60 and 61 communicate with the interior of the cylinder 59 one adjacent each end. Any suitable type of control means may be used to admit fluid under pressure to either end of the cylinder or exhaust it therefrom. When fluid under pressure is admitted to the cylinder 59 through the conduit 60 the piston 58 is forced downward thereby rocking the shaft 52 and the cams 50 which in turn raise the core plug 16 upward to an operative position. When the fluid is exhausted from the cylinder 59 through the conduit 60 and admitted 30 thereinto through the conduit 61 the piston 58 is forced upward thereby rocking the shaft 52 and the cams 50 to a position wherein the cams allow the core plug 16 to move downward a slight 35 distance.

At each corner of the mould 12, I provide a post 62. The posts adjacent their upper ends are secured to standards 63, which are connected by transverse members 63'. Slidably mounted on 45 each of the posts 62, I provide a hollow sleeve 64 which is slidably mounted in a cap member 65 of a cylinder 66. The sleeve 64 extends downward into the cylinder 66 where it is provided with an enlarged piston head 67.

50 The body section 14 of the mould 12 includes bearing members 68 in which the sleeves 64 are slidably positioned and the top section 15 includes similar bearing members 69. The skirt plunger 17 is shown as mounted on a frame member 70 55 which includes bearing members 71 in which the rear sleeves 64 are positioned. Secured to the rear sleeves 64 I provide collars 72 which engage the under surface of the bearings 71 and similar collars 73 which engage the upper surface of 60 the bearings 71.

Secured to all the sleeves 64 I provide collars 74 which are adapted to engage the under faces of the bearings 69 and collars 75 which are adapted to engage the under faces of the bearings 68. 65 Also secured to the sleeves 64 I provide collars 76 which engage the upper faces of the bearings 69 and collars 77 which engage the upper faces of the bearings 68. The collars 74 and 75 are spaced below the under faces of their associated 70 bearings so that when the sleeves 64 move upward the collars 74 engage their associated bearings 69 first and upon continued upward movement of the sleeves the collars 75 thereafter engage their associated bearings 68.

75 As indicated at 78 and 79 fluid conduits com-

municate with the interior of the cylinders 66 one adjacent each end of each cylinder. Any suitable type of control means may be used to admit fluid under pressure to either end of the cylinders or exhaust it therefrom. When fluid 5 under pressure is admitted to the cylinders 66 through the conduits 78 the pistons 67 and the sleeves 64 are simultaneously forced upward. As the sleeves 64 thus move upward the skirt plunger 17 is first moved upward a predetermined distance 10 then as the sleeves continue to move upward carrying therewith the skirt plunger the collars 74 engage the bearings 69 and move the top section 15 upward a predetermined distance. As the sleeves continue to move upward carrying there- 15 with the skirt plunger and the top section the collars 75 engage the bearings 68 and move the body section 14 upward. Thereafter the skirt plunger 17, the top section 15 and the body section 14 move upward together to a predetermined 20 height. When the fluid in the cylinders is exhausted from the cylinders through the conduits 78 the sleeves 64 move downward whereupon the body section 14, the top section 15 and the skirt plunger 17 return to their initial positions. 25

After the various portions of the mould 12 have returned to their initial positions fluid under pressure is admitted to the cylinders 66 through the conduits 79 thereby putting a downward pressure on the piston heads 67 which urge 30 the sleeves downward which through the medium of the collars 73, 76 and 77 urge their associated mould sections into tight operative engagement.

The mould base 13 includes a continuous serpentine passageway, as indicated at 80, through 35 which a fluid such as oil is circulated to maintain it at a predetermined temperature, the body portion 14, the top section 15, the plugs 33, the skirt plunger 17 and the core plunger 16 all include similar passageways 81, 82, 83, 84 and 85, 40 respectively, for the same purpose. Oil for circulation through the passageways 81, 82, 83, 84 and 85 may be conducted thereto and therefrom in any suitable manner.

In operation the mould sections 14, 15 and 17 45 are raised and the core plunger 16 is lowered as previously described. A sand core 38 is then positioned in each of the recesses 37 of the plug members 33. The mould sections 14, 15 and 17 are then lowered to operative positions and the core plunger 16 raised to an operative position. The pouring plug 45 is then positioned in the recesses 43 and 44 of the top section and thereafter moulten material such as metal or glass 55 is poured into the recess 46 of the pouring plug 45. The moulten material runs through the apertures 47 of the pouring plug 45 into spaces provided in the mould for forming the sections of the bath tub.

After the moulten metal has been poured the 60 core plunger 16 is lowered and after a desired interval the skirt plunger 17, the top section 15 and the body section 14 are raised in the manner previously described. After the mould sections have been raised the bath tub 18 is raised upward 65 and removed out of the mould base in any desired manner. Thereafter the recess 37 of the plug members 33 are cleaned out and new core members 38 placed therein and the recesses 43 and 44 of the top section 15 cleaned out and a 70 new pouring plug 45 placed therein whereupon the mould mechanism 10 is reset to an operative position to receive another pouring of moulten material.

From the foregoing description it will be ap- 75

parent that I have provided a novel mould mechanism which is simple in construction and highly efficient in use.

Having thus described my invention, I claim:

5. 1. In a moulding apparatus, a support, a mould on said support, said mould including a base having a flange upwardly projecting therefrom, a body portion on said base, said body portion being substantially U-shaped and coacting with said base and said upstanding flange to form a mould cavity, a top section on said body portion, said top section being apertured to receive a pouring plug, a skirt plunger mounted to move into said mould, means to move said skirt plunger, said top section and said body portion independently and in order, a core in said mould and means to move said core in a direction opposite to the direction of movement of said skirt plunger, said top section and said body portion.
10. 2. In a mould for casting a receptacle which includes a hollow body portion and a skirt portion integral therewith and spaced therefrom and wherein a rib is arranged adjacent to each end of the receptacle, each rib having one end integral with the receptacle body and at the opposite end integral with the skirt portion, said mould including a body portion having a recess therein shaped to form a portion of the outer surface of said receptacle body and the outer surface 30 of said skirt, a skirt plunger member, said skirt plunger being movable relative to said mould body, said mould body having a recess therein at each end, each of said spaced recesses having a sand core member therein and each of said 35 said core members including a portion shaped to form one of said ribs.
15. 3. In a mould for casting a receptacle which includes a hollow body portion and a skirt portion integral therewith and spaced therefrom and wherein a rib is arranged adjacent to each end of the receptacle each rib having one end integral with the receptacle body and the opposite end integral with the skirt portion, said mould including a body portion having a recess therein shaped to form a portion of the outer surface of said receptacle body and the outer surface of said skirt, a skirt plunger member, said skirt plunger being movable relative to said mould body, one face of said skirt plunger being shaped to form the remainder of said outer surface of said receptacle body and the opposite surface of said skirt plunger being shaped to form the inner surface of said skirt, said mould body having a pair of spaced recesses therein at each end, each of said spaced recesses having a sand core member therein and each of said sand core members including a portion shaped to form one of said ribs.
20. 4. In a mould for casting, said mould including a base portion, a body portion and a top portion, said portions being independently movable, said portions being shaped to form a receptacle, said top portion and said body portion having a chamber therein, a plug member positioned in said chamber, said plug member extending downward into said chamber of said mould body portion, said plug member having a recess therein, a sand core member in said plug recess, said sand core member being shaped to form a rib, a skirt plunger member, said skirt plunger being positioned in said top portion chamber and being upwardly movable relative thereto, said skirt plunger extending downwardly into said mould body, said skirt plunger being shaped to form a portion of a skirt, and a core member positioned in said mould and being shaped to form the inner surface of said receptacle body.
25. 5. In a mould for casting a receptacle which includes a hollow body portion and a skirt portion integral therewith and spaced therefrom and wherein a rib is arranged adjacent each end of the receptacle, said mould including a body portion having a recess therein shaped to form a portion of the outer surface of said receptacle body and the outer surface of said skirt, a skirt plunger member, said skirt plunger being movable relative to said mould body, one face of said skirt plunger being shaped to form the remainder of said outer surface of said receptacle body the opposite surface of said skirt plunger being shaped to form the inner surface of said skirt, said mould body having a pair of spaced recesses therein each of said spaced recesses having a sand core member therein and each of said sand core members being shaped to form one of said ribs, and a core member, said core member being shaped to form the inner surface of said hollow body, said core member being movable relative to said mould body.
30. 6. In a mould for casting a metal receptacle which includes a hollow body portion and a skirt, said mould including a base having a plane upper face and including an upwardly projecting flange at one side, the face of said flange adjacent said plane face being shaped to form a portion of the outer surface of the skirt, said plane face of said base being adapted to form the upper surface of the receptacle, said base having an aperture, a body portion positioned on said base and movable upwardly relative thereto, said body portion having an aperture arranged to form a portion of the outer surface of the receptacle body, said body portion having a chamber adjacent the skirt forming portion of said mould, a top section positioned on said mould body and movable upwardly relative thereto, the under face of said top section having a recess shaped to form a portion of the outer surface of the sides and bottom of said receptacle body, said top section having a chamber therein, a skirt plunger member positioned in said top section chamber and movable upwardly relative thereto, said skirt plunger extending downwardly into said chamber of said mould body, one face of said skirt plunger being shaped to form a portion of the outer surface of said receptacle body and the opposite face of said skirt plunger being shaped to form the inner face of said skirt, a core member movably positioned in said base aperture in said mould body aperture and in said top section under-recess.
35. 7. In a mould for casting an inverted receptacle which includes a hollow body and a skirt, said mould including a base having a plane upper face and an upwardly projecting flange at one side, the face of said flange adjacent said plane face being shaped to form a portion of the outer surface of said skirt, said plane face of said base being adapted to form the upper surface of said receptacle, a mould body portion having an aperture shaped to form a portion of the outer surface of said receptacle body, said mould body portion having a chamber adjacent the skirt forming portion of said mould, said mould including a top section positioned on said mould body and upwardly movable relative thereto, the under face of said top section having a recess shaped to form a portion of the outer surface of the sides and bottom of said receptacle body, said top section having an aperture com- 75

5. municating with said recess of said top section, a
pouring plug in said aperture, said top section
having a chamber therein, a skirt plunger mem-
ber, said skirt plunger being removably posi-
5. tioned in said top section chamber, said skirt
plunger extending downwardly into said chamber
of said mould body, one face of said skirt plunger
being shaped to form a portion of the outer sur-
face of said receptacle body and the opposite
10. face of said skirt plunger being shaped to form
the inner face of said skirt and a core member
positioned in said base aperture in said mould
body aperture and in said top section under-
recess, said core member being movable relative
15. to said mould base, said mould body and said
mould top section, said core member being shaped
to form the inner surface of said receptacle body.
8. In a mould for casting a metal receptacle
which includes a hollow body portion and a skirt
20. said mould including a base having a plane up-
per face and including an upwardly projecting
flange at one side, the face of said flange ad-
jacent said plane face being shaped to form a
portion of the outer surface of the skirt, said
25. plane face of said base being adapted to form
the upper surface of the receptacle, said base
having an aperture, a body portion positioned on
said base and movable upwardly relative thereto,
said body portion having an aperture arranged
- to form a portion of the outer surface of the
receptacle body, said body portion having a
chamber adjacent the skirt forming portion of
said mould, a top section positioned on said mould
body and movable relative thereto, said top sec-
tion having a recess shaped to form a portion
of the outer surface of the sides and bottom of
said receptacle body, said top section having a
chamber therein, a skirt plunger member posi-
10. tioned in said top section chamber and movable
upwardly relative thereto, said skirt plunger ex-
tending downwardly into said chamber of said
mould body, one face of said skirt plunger being
shaped to form a portion of the outer surface
15. of said receptacle body and the opposite face of
said skirt plunger being shaped to form the inner
face of said skirt, a core member movably
positioned in said base aperture in said mould
body aperture and in said top section recess, said
core member being shaped to form the inner sur-
face of said receptacle body, means to move said
core member, means to raise said mould body,
said top section and said skirt plunger to an
inoperative position and means whereby in rais-
ing said mould sections said skirt plunger, said
20. top section and said mould body start their up-
ward movement in order.

MATTHEW WAGNER.
